US0D1107641S

(12) **United States Design Patent** (10) Patent No.: **US D1,107,641 S**
(45) Date of Patent: ** Dec. 30, 2025

(54) **TIRE SIDEWALL**

(71) Applicant: **TIRE GROUP INTERNATIONAL, LLC**, Miami, FL (US)

(72) Inventor: **Antonio R. Gonzalez**, Miami, FL (US)

(73) Assignee: **TIRE GROUP INTERNATIONAL, LLC**, Miami, FL (US)

(**) Term: **15 Years**

(21) Appl. No.: **29/935,849**

(22) Filed: **Apr. 3, 2024**

(51) LOC (15) Cl. **12-15**

(52) U.S. Cl.

USPC **D12/605**

(58) **Field of Classification Search**

USPC D12/604, 605

(57) **CLAIM**

The ornamental design for tire sidewall as shown and described.

DESCRIPTION

FIG. 1 is a front-top view illustrating my design for a tire sidewall;

FIG. 2 is a front view thereof;

FIG. 3 is a rear view thereof;

FIG. 4 is a side view thereof;

FIG. 5 is a side view thereof;

FIG. 6 is a top view thereof; and,

FIG. 7 is a bottom view thereof.

The broken lines in the drawings are included for purposes of illustrating portions of the tire sidewall, but form no part of the claimed design.

1 Claim, 5 Drawing Sheets
